UNITED STATES PATENT OFFICE.

JOHN VAN BUREN, OF BROOKLYN, NEW YORK.

SEALING METHOD AND MECHANISM FOR CONTAINERS.

Application filed November 5, 1926. Serial No. 146,427.

This invention relates to sealing mechanism for containers and to a method of sealing containers.

One of the most difficult problems in handling greasy or oily substances in cans or containers having removable covers, is to prevent the substance from leaking out of the can around the cover and to prevent air from leaking in thereby causing the substance to deteriorate. The usual method of procedure is to place the cover on the cover end of the can or container, then place the substance in the can and permanently close the other end of the container.

It has been found that an effective seal around the cover can be obtained by crimping the cover or forcing the cover over a liner of cellophane or thin transparent material in the nature of paper. This material is, however, very difficult to handle as it tears and curls very easily.

This invention has for its salient object to provide means for applying material, such as that specified, to cans or containers.

Another object of the invention is to provide cutting mechanism for cutting the material to fit the cans or containers after it has been fed in a strip over the top of the can.

Another object of the invention is to provide a simple, practical and inexpensive method of sealing containers or cans.

Further objects of the invention will appear from the following specification, taken in connection with the drawings, which form a part of this application, and in which

Fig. 1 is a top plan view of a machine constructed in accordance with the invention;

Fig. 2 is a longitudinal, sectional elevation taken substantially on line 2-2 of Fig. 1;

Fig. 3 is a transverse, sectional elevation taken substantially on line 3-3 of Fig. 1;

Fig. 4 is a sectional elevation taken substantially on line 4-4 of Fig. 3;

Fig. 5 is an enlarged plan view of the cutting mechanism and associated parts;

Fig. 6 is a sectional elevation taken substantially on lines 6-6 of Fig. 1.

The invention briefly described consists of mechanism for supporting and feeding a plurality of tubular containers, means for feeding and securing an elongated strip of

material along the tops of the containers and means for severing this material at each side of each container. In the particular form of the invention shown, viscous material, such as a lubricant or grease coating, is applied to the tops of the containers and the strip of material is pressed against the tops. The cutting mechanism operates intermittently and cuts the strip at each side of each container, thus leaving a substantially circular disk of the transparent material secured to the top of each container. The covers are then crimped around the upper edges of the cans or containers crimping the disk and forming a tight seal. Further details of the invention will appear from the following description.

Can supporting and feeding mechanism.

In the particular embodiment of the invention illustrated, the supporting and feeding mechanism is carried by supporting standards 10 and 11 which are connected by cross bars 12. The cans 13 are supported on three longitudinally extending supporting rails or bars 14, 15 and 16, these rails being spaced apart to provide longitudinal slots or openings 17 therebetween for a purpose hereinafter described.

The cans are fed by means of an endless chain consisting of a plurality of links 20 and mounted on sprockets 21 and 22. Certain of the links 20 are extended upwardly or have formed thereon lugs 23 to which are secured upwardly extending pins 24 and 25 which are adapted to engage and feed the cans, these pins extending upwardly through the slots 17 as shown in Fig. 5. The link pins 30 are extended beyond the links as shown at 31 and 32 and have mounted thereon rollers 34 and 35 which ride on tracks 36 and 37 carried by the cross bars 12. Since the rollers 34 and 35 run on the tracks 36 and 37, the chain will be supported by the tracks. Elongated strips 38 and 39 are supported above the tracks by spacers 40 and 41.

From the foregoing description it will be seen that as the sprockets are rotated, the chain and the pins carried thereby will feed the cans along the rails 14, 15 and 16.

Lubricant applying mechanism.

The lubricant or grease, such as vaseline, is applied to the tops of the cans or containers in the following manner. The vase-

line or other suitable lubricant is placed in a receptacle 50 secured by screws 51 at one end and supported on set screws 52 at the other end, the screws 52 engaging beneath 5 lugs 53. A roller 54 dips into the lubricant 55 and transfers the material to a roller 56 geared to the roller 54. Roller 56 in turn transfers the lubricant to a roller 57 which is positioned as shown in Fig. 2 to engage 10 the tops 58 of the cans 13 as they are fed along the rails by the chain.

Strip feeding mechanism.

The elongated strip of cellophane or trans- 15 parent material is contained in a supply roll 60 mounted in supports 61 and from the roll extends between feeding rollers 62 and 63 by means of which it is fed downwardly to the tops of the cans. The feed roll 62 20 is driven by a sprocket and chain connection from an idler shaft 65 which is geared to the shaft 66 of the sprocket 21. The shaft 70 of the feed roll 62 is also connected by a sprocket and chain connection to drive 25 the shaft 71 of the roll 57.

As the strip of material is fed between the rolls 62 and 63, it passes downwardly and is pressed by the roll 62 against the tops 30 of the cans as they are fed beneath this roll.

Cutting mechanism.

The elongated strip of material is cut at each side of each container so that a substantially circular disk of material is placed 35 across the top of each container. This cutting mechanism operates intermittently and during the feeding action of the chain on the cans. The cutting mechanism comprises a pair of stationary knives 80 and 81 ad- 40 justably mounted as shown at 82 on supports 83. These knives, as will be seen from the showing in Fig. 4, are disposed above the path of the elongated strip of material. The knives, as clearly illustrated in Fig. 5, 45 are curved longitudinally and extend across the strip, the central portions 85 and 86 being disposed adjacent to but spaced from each other and the end portions as shown at 87 and 88 curving or diverging away from 50 each other. It will be noted that the curvature of the knives 80 and 81 conforms substantially to the curvature of the cans.

The cutting mechanism also comprises two sets of blades adapted to coat with the 55 stationary knives 80 and 81. These two sets are mounted at the longitudinal edges of the elongated strip on shafts 90 and 91. The set of blades mounted on the shaft 90 consists of a pair of blades 92, 93, each blade 60 being secured at one end to the shaft and the blades converging from their secured ends to their free ends. In a similar manner, blades 95 and 96 are secured to the shaft 91.

65 The blades 92, 93, 95 and 96 are preferably

formed of resilient material and are so mounted as to coat with the stationary knives 80 and 81 and to have a shearing action with respect thereto. It will be noted that the blades carried by the shafts 90 and 91 are adapted to move from a position below the strip into coaction with the knives 80 and 81, thus severing the strip.

The blades are rotated upwardly across the strip during their cutting operation in 70 the following manner.

Shafts 90 and 91 have secured thereto bevel gears 100 and 101 which mesh with gears 102, 103 carried by a shaft 104. The shaft 104 has a gear 105 mounted thereon which meshes with the gear 106 carried by a shaft 107. The shaft 107 has a Geneva wheel 108 secured thereto which is driven by a pin 109 carried by a shaft 110 geared as shown at 111 to the shaft 70 of the feed 85 roll 62.

From the foregoing description it will be seen that the blades 92 and 93 and the blades 95 and 96 will be rotated about the shafts 90 and 91 inwardly and upwardly with reference to the strip of material, thus coacting with the knives 80 and 81 in shearing or cutting the strip. In Fig. 5 it will be seen that a disk 112 has been secured to the top of the right hand can, that the cutting 95 mechanism is completing the cutting of the disk 113 for the second can from the right, and that the cutting mechanism is cutting the right hand side of the material which covers the can 114.

In order to secure the strip against movement during the cutting operation, means is provided for pressing the strip against the tops of the two cans between which the strip is cut. This means consists of presser feet 105 120 and 121 carried by posts or spindles 122, 123 slidably mounted in supports 83. The posts 122, 123 have heads 124, 125 at their upper ends and reduced extensions 126, 127 above the heads. Springs 128 and 129 engage the heads and normally hold the heads and pressure feet in inoperative or elevated position. The heads are engaged by ends 130, 131 of levers 132 and 133 which are actuated by cams 134 and 135 carried by the 115 knife operating shaft 92.

Thus, when the movable knives are actuated to cut the strip, the strip will be held against the tops of the cans by the presser feet.

It will be clear that simple, practical mechanism and a simple and practical method has been provided for supporting and feeding a plurality of tubular containers for securing an elongated strip of cellophane or 125 like material to the tops of the containers and for severing the strip in a manner to leave a disk of the material positioned on the top of the can.

After the cellophane disks have been ap- 130

plied to the tops of the cans in the manner specified, the cans are placed in another machine and the covers are secured to the tops and the cellophane is crimped around the 5 upper edge of the cans with the cover. The cellophane thus forms a lining and seal between the can covers and the contents of the cans. The lubricant prevents the cellophane strip from curling, facilitates the crimping 10 operation and prevents the cellophane from cracking or breaking during the crimping operation.

Although one specific embodiment of the invention has been particularly shown and 15 described, it will be understood that the invention is capable of modification and that changes in the construction and in the arrangement of the various cooperating parts may be made without departing from the 20 spirit or scope of the invention, as expressed in the following claims.

What I claim is:

1. In combination, means for supporting and feeding a plurality of containers, means 25 for applying lubricant to one end of each container, means for feeding an elongated strip of material across said ends and into engagement therewith, and means movable toward the longitudinal center of the sheet 30 from the longitudinal edges thereof for severing said sheet at each side of each container.

2. In combination, means for supporting and feeding a plurality of containers, means 35 for applying viscous material to one end of each container, means for feeding an elongated strip of material across said ends and into engagement therewith, and rotatable means for severing said sheet at each side of 40 each container.

3. In combination, means for supporting and feeding a plurality of containers, means 45 for applying lubricant to one end of each container, means for feeding an elongated strip of material across said ends and into engagement therewith, and rotatable means movable toward the longitudinal center of the sheet from the longitudinal edges thereof for severing said sheet at each side of 50 each container.

4. In combination, means for supporting and feeding a plurality of containers, means 55 for applying viscous material to one end of each container, means for feeding an elongated strip of material across said ends and into engagement therewith, curved stationary knives positioned above the strip of material and movable knives at the edges of the material adapted to swing between adjacent 60 containers and coact with said stationary knives to sever the strip between adjacent containers.

5. In combination, means for supporting and feeding a plurality of containers, means 65 for applying lubricant to one end of each

container, means for feeding an elongated strip of material across said ends and into engagement therewith, curved stationary knives positioned above the strip of material and curved flexible knives rotatably mounted 70 at the edges of the material adapted to swing between adjacent containers and coact with said stationary knives to sever the strip between adjacent containers.

6. In combination, means for supporting 75 and feeding a plurality of containers, means for applying lubricant to one end of each container, means for feeding an elongated strip of material across said ends and into engagement therewith, a pair of longitudinally curved stationary knives disposed above and extending across the strip of material, said knives having their central portions disposed adjacent to but spaced from each other and having their ends diverging 85 from each other and rotatable knives movable between adjacent containers and between said stationary knives and adapted to coact with the stationary knives in shearing relation with respect thereto. 90

7. In combination, means for supporting and feeding a plurality of tubular containers, means for applying viscous material to one end of each container, means for feeding an elongated strip of material across said 95 ends and into engagement therewith, a pair of longitudinally curved stationary knives disposed above and extending across the strip of material, said knives having their central portions disposed adjacent to but spaced from each other and having their ends diverging from each other and rotatable, resilient knives movable between adjacent containers and between said stationary knives and adapted to coact with the 100 stationary knives in shearing relation with 105 respect thereto.

8. In combination, means for supporting and feeding a plurality of tubular containers, means for applying viscous material to 110 one end of each container, means for feeding an elongated strip of material across said ends and into engagement therewith, a pair of longitudinally curved stationary knives disposed above and extending across the strip of material, said knives having their central portions disposed adjacent to but spaced from each other and having their ends diverging from each other and a pair 115 of rotatable knife blades at each edge of the strip movable into coacting relation with said stationary knives and adapted to sever the strip between adjacent containers.

9. In combination, means for supporting and feeding a plurality of containers, means 125 for applying grease to one end of each container, means for feeding an elongated strip of material across said ends and into engagement therewith, a pair of longitudinally curved stationary knives disposed above and 130

- elongated strip of material across the ends of a plurality of tubular containers, a pair of stationary knives supported above and extending across said strip and a pair of resilient blades movable upwardly from opposite longitudinal edges of the strip into coacting shearing relation with each stationary knife and adapted to sever said strip. 20. In combination, means for feeding an elongated strip of material across the ends of a plurality of tubular containers, a pair of stationary knives supported above and extending across said strip, the longitudinal centers of said knives being disposed adjacent each other and the remaining portions of the knives curving away from each other, and a pair of blades movable upwardly into coacting relation with each stationary knife and adapted to sever said strip. 21. In combination, means for feeding an elongated strip of material across the ends of a plurality of tubular containers, a pair of stationary knives supported above and extending across said strip and a pair of blades movable upwardly between said knives and into coacting shearing relation with each stationary knife and adapted to sever said strip. 22. In combination, means for feeding an elongated strip of material across the ends of a plurality of tubular containers, a pair of stationary knives supported above and extending across said strip and a pair of blades movable upwardly from opposite longitudinal edges of the strip between said knives and into coacting shearing relation with each stationary knife and adapted to sever said strip. 23. In combination, means for supporting and feeding a plurality of containers, means for applying lubricant to one end of each container, means for feeding an elongated strip of material across said ends and into engagement therewith, a pair of longitudinally curved stationary knives disposed above and extending across the strip of material, the central portions of said knives being spaced from but disposed adjacent each other and the end portions diverging away from each other and a pair of cutting blades adapted to coact with each stationary knife. 24. In combination, means for feeding an elongated strip of material across the ends of a plurality of tubular containers, a pair of longitudinally curved stationary knives disposed above and extending across the strip of material, the central portions of said knives being spaced from but disposed adjacent each other and the end portions diverging away from each other and a pair of cutting blades adapted to coact with each stationary knife. 25. In combination, means for supporting and feeding a plurality of containers, means for feeding an elongated strip of material across the ends of a plurality of tubular containers, a pair of stationary knives supported above and extending across said strip and a pair of blades movable upwardly from opposite longitudinal edges of the strip into coacting shearing relation with each stationary knife and adapted to sever said strip, and means for holding the material against the tops of the containers during the severing operation. 26. In combination, means for feeding an elongated strip of material across the ends of a plurality of containers, means including a stationary knife and a movable blade for severing said material at each side of each container, and means for holding the material against the tops of the containers during the severing operation. 27. In combination, means for feeding an elongated strip of material across the ends of a plurality of containers, means including a stationary knife and a movable blade for severing said material at each side of each container, and intermittently operating means for holding the material against the tops of the containers during the severing operation. 28. In combination, means for feeding an elongated strip of material across the ends of a plurality of containers, means including a stationary knife and a movable blade for severing said material at each side of each container, and means for holding the material against the tops of the containers between which the strip is being severed during the severing operation. 29. In combination, means for feeding an elongated strip of material across the ends of a plurality of containers, means including a stationary knife and a movable blade for severing said material at each side of each container, and presser feet for holding the material against the tops of the containers during the severing operation. 30. In combination, means for feeding an elongated strip of material across the ends of a plurality of containers, a pair of stationary knives supported above and extending across said strip, a pair of blades movable upwardly into coacting shearing relation with each stationary knife and adapted to sever said strip, and means for holding the material against the tops of the containers during the severing operation. 31. In combination, means for feeding an elongated strip of material across the ends of a plurality of containers, a pair of stationary knives supported above and extending across said strip, a pair of blades movable upwardly from opposite longitudinal edges of the strip into coacting shearing relation with each stationary knife and adapted to sever said strip, and means for holding the material against the tops of the containers during the severing operation. 32. In combination, means for feeding an elongated strip of material across the ends of a plurality of tubular containers, a pair of stationary knives supported above and ex-

tending across said strip, a pair of resilient blades movable upwardly between said knives and into coacting shearing relation with each stationary knife and adapted to sever said strip, and means for holding the material against the tops of the containers during the severing operation.

33. In combination, means for supporting and feeding a plurality of containers, means for feeding an elongated strip of material into contact with the tops of said containers, mechanism including stationary knives above the strip and blades movable between adjacent containers for severing said strip of material, and means operable during the operation of the movable blades for holding the material against the tops of the containers during the severing operation.

34. In combination, means for supporting and feeding a plurality of containers, means for feeding an elongated strip of material

into contact with the tops of said containers, mechanism including stationary knives above the strip and blades movable between adjacent containers for severing said strip of material, and intermittently operating means operable during the operation of the movable blades for holding the material against the tops of the containers during the severing operation. 25

35. A method of sealing the ends of containers which consists of feeding a plurality of containers with their upper ends in alignment, applying lubricant to the tops of said containers, feeding a continuous strip of sealing material along the tops of said containers, holding the strip against the tops of adjacent containers, and severing the strip between said adjacent containers. 30

In witness whereof, I have hereunto set my hand. 40

JOHN VAN BUREN.
